UNITED STATES PATENT OFFICE.

CONRAD JOSEPH TRITSCHLER, OF ANERLEY, LONDON, ENGLAND.

STAGE APPARATUS.

1,332,085.

Specification of Letters Patent.

Patented Feb. 24, 1920.

Application filed October 18, 1919. Serial No. 331,693.

To all whom it may concern:

Be it known that I, CONRAD JOSEPH TRITSCHLER, a subject of the King of Great Britain, and a resident of Anerley, London, S. E., 5 England, have invented a new and Improved Stage Apparatus, of which the following is a full, clear, and exact description.

The object of the invention is to provide a new and improved stage apparatus, more 10 especially designed for vividly producing the effect of an aeroplane, dirigible or other air craft traveling in the night, appearing to be set on fire interiorly, with the flames eventually burning out and the air craft 15 dropping down to earth. Another object is to provide an exceedingly simple and inexpensive means for accomplishing the desired result.

With these and other objects in view, the 20 invention consists of certain novel features of construction, as hereinafter shown and described and then specifically pointed out in the claims.

A practical embodiment of the invention 25 is represented in the accompanying drawings forming a part of this specification, in which similar characters of reference indicate corresponding parts in all the views.

Figure 1 is a front elevation of a stage 30 provided with the improved stage apparatus;

Fig. 2 is a cross section of the same;

Fig. 3 is an enlarged face view of the 35 representation of an aerial vessel; and

Fig. 4 is a cross section of the same on the line 4—4 of Fig. 3.

Across the stage 10 is stretched a screen 11, preferably of diaphanous material such as a transparent or translucent cloth, and 40 on the rear face of this screen is fitted one open side of a hollow body of box-like structure representing in outline an aeroplane, a dirigible or other similar air craft 12. On the top of this hollow body 12 is arranged a 45 box-like compartment 13 open at the front side and appearing in outline like tongues of flame, as will be readily understood by reference to Figs. 1 and 3. The body 12 is preferably suspended by wires or other sup-

50 porting means 14 from the flies and adapted to be moved along by the wires 14 to give the body 12 the appearance of traveling across the stage. Within the body 12 and near the bottom thereof is arranged a row of 55 low voltage (4 volts) pea lights 20 connected by wires with an accumulator, to be

operated from the same by their own dimmers. By the arrangement described, the lights 20 when switched on illuminate the interior of the body 12 with a white light. 60 Within the body 12 are arranged strong power red colored filament lamps 25, preferably two in number, and connected by wires 26 with a switch 27 under the control of the operator in charge of the stage apparatus. 65 Within the extension compartment 13 is arranged a series of mixed red and amber fire colored filament lamps 30 connected by wires 31 with a switch 32 under the control of the operator in charge of the stage apparatus. 70 By the arrangement described, the body 12 can be interiorly illuminated by the lamps 20 with a white light so that the aerial vessel appears on the darkened stage visible in the sky. The operator next switches on the 75 lamps 25 thus illuminating the body 12 interiorly with a red light thereby producing the effect of the aerial vessel being on fire. The operator next switches on the series of lamps 30 thus producing the effect of flames 80 bursting from the vessel. After the lights 30 are lighted, the operator by manipulating the wires 14 can let the vessel drop endwise downward thus producing the final effect of destruction of the aerial vessel and its dropping 85 to the ground.

In order to heighten the effect, use is preferably made of a miniature search light 40 preferably of the construction more fully shown and described in a companion application Serial Number 331,692 filed by me on October 18, 1919. This search light 40 is preferably mounted in front of the screen 11 above the stage floor and it serves to direct a beam of light against the under side 90 of the body 12, the beam also appearing on the screen 11. In practice, the search light 40 is mounted by pivots 41 on a support 42, which may be a piece of scenery set on the stage floor or representation of a ship 10 or other similar moving part mounted to travel across the stage in front of the screen. By rocking the search light 40 on its pivot 41, the effect of a search light searching the sky is produced.

It is understood that the open side of the body 12 and its compartment 13 fit snugly against the rear face of the screen 11, and hence the rays of light from the lamps do not illuminate the entire surface of the screen 110 and thus spoil the illusion, but only illuminates the portion of the screen covered by

the body 12 and its compartment 13 thus vividly disclosing the outline of the body when the lamps 20 and 30 are lighted, and disclosing the flame portion when the latter is illuminated by the lamps 30.

It will be noticed that the diaphanous screen diffuses light from the lamps sufficiently to render the lamps invisible to the audience.

Having thus described my invention, I claim as new and desire to secure by Letters Patent:

1. A stage apparatus, comprising a diaphanous screen, a body representing an object fitting against the screen, and illuminating means arranged within the body and of different colors to successively illuminate the body interiorly with a view to first display the object in a natural condition and then as set on fire.

2. A stage apparatus, comprising a diaphanous screen, a body representing an object having an open side fitting against the said screen, and illuminating means of different colors arranged within the said body to illuminate the latter interiorly and successively, first with a white light to display the body in a natural condition and then with a red light to display the body as set on fire interiorly.

3. A stage apparatus, comprising a diaphanous screen, a body representing an object having an open front face fitting against the screen, the body having an extension compartment representing flames in outline, two sets of illuminating means arranged within the said body and of different colors, an illuminating means in the said extension compartment, and controlling means under the control of an operator for successively switching on the said illuminating means to display the object first in a natural condition, then as set on fire interiorly, and finally as appearing with flames bursting out from the body.

4. A stage apparatus, comprising a diaphanous screen, a body representing an object fitting against the screen, means for moving the said body along the said screen, and illuminating means arranged within the body and of different colors to successively illuminate the body interiorly with a view to first display the object in a natural condition and then as set on fire.

5. In a stage illusion, a hollow body open

at one side and representing in outline an aerial vessel, a compartment extending from the said body and likewise open at the side, two sets of differently colored electric illuminating means in the said body, and an electric illuminating means in the said compartment.

6. In a stage illusion a hollow body open at one side and representing in outline an aerial vessel, a compartment extending from the said body and likewise open at the side, two sets of differently colored electric illuminating means in the said body, and an electric illuminating means in the said compartment and provided with differently colored bulbs arranged alternately.

7. A stage apparatus, comprising a diaphanous screen on a stage, a hollow body open at one side and fitting against the rear face of the said screen, means illuminating the interior of the said body, and a miniature search light in front of the said screen adjacent the floor of the stage and adapted to direct a beam of light upward onto the said screen and onto the lower portion of the said body.

8. A stage apparatus, comprising a diaphanous screen on a stage, a hollow body open at one side and fitting against the rear face of the said screen, means illuminating the interior of the said body, a miniature search light in front of the said screen adjacent the floor of the stage and adapted to direct a beam of light upward onto the said screen and onto the lower portion of the said body, means for imparting motion to the said body, and means for rocking the said search light from the said beam of light to follow the traveling body.

9. A stage apparatus, comprising a diaphanous screen on a stage, a hollow body open at one side and fitting against the rear face of the said screen, means illuminating the interior of the said body, a miniature search light in front of the said screen adjacent the floor of the stage and adapted to direct a beam of light upward onto the said screen and onto the lower portion of the said body, means for imparting motion to the said body, means for rocking the said search light for the said beam of light to follow the traveling body, and traveling means carrying the said search light across the stage.

CONRAD JOSEPH TRITSCHLER.
